UNITED STATES PATENT OFFICE.

LEWIS T. HOUGHTON, OF WORCESTER, MASSACHUSETTS.

THREAD-GUIDE FOR SPINNING OR TWISTING MACHINES.

1,070,036.

Specification of Letters Patent. Patented Aug. 12, 1913.

Application filed October 12, 1901, Serial No. 79,151. Renewed February 12, 1908. Serial No. 415,637.

To all whom it may concern:

Be it known that I, Lewis T. HOUGHTON, a citizen of the United States, residing at Worcester, in the county of Worcester and State of Massachusetts, have invented a new and useful Thread-Guide for Spinning or Twisting Machines, of which the following is a specification.

This invention relates to an improved thread-guide for spinning or twisting machines, and to an improved guide-support.

The special objects of this invention are to provide an improved thread guide of porcelain or similar material, and to combine said thread-guide with a thread-guide support of special construction, so as to provide a device which is especially adapted for wet spinning or twisting; that is to say, which is especially applicable for guiding wet or damped strands, although certain features of this invention may, if desired, be used to advantage for ordinary dry spinning or twisting.

To these ends, this invention consists of the thread-guide, and of the combinations of parts therewith, as hereinafter described, and more particularly pointed out in the claim at the end of this specification.

In the accompanying drawing, Figure 1 is a plan view of a thread-guide for spinning or twisting machines constructed according to my invention. Fig. 2 is a side view of the same, Fig. 3 is a central transverse sectional view thereof, Fig. 4 is a bottom plan view of the form of thread-guide-support which I prefer to employ, Fig. 5 is an enlarged transverse sectional view illustrating the manner in which the thread-guide may be forced or snapped down into its socket, and Fig. 6 is a similar view of the parts when the thread-guide is secured in place.

In a prior United States Patent No. 677,938 granted to me July 9, 1901, I have shown and claimed a sheet metal support for the thread-guide of a spinning or twisting machine.

The especial object of my present invention is to provide an improved and perfected form of thread-guide constructed according to my prior patent before referred to, which is especially designed and adapted for wet spinning.

Referring to the accompanying drawing, and in detail, A designates a wooden strip, which may be hinged to the frame of a spinning or twisting machine by means of ordinary

hinges, as in the usual practice. Fastened on to the front of the wooden piece A is a sheet metal strip 10, which may be held in place by means of screws 12. Along its upper edge the strip 10 is provided with integral fingers or projections 11, which are bent back or rolled to form a socket for receiving the wire which forms the hinge-pin for a finger-head, as hereinafter described. By applying the strip 10 to the front of the wooden finger-head-board A, I have found in practice that this will strengthen and prevent the wooden finger-head-board from warping or twisting out of shape.

A finger-head as herein illustrated is stamped out of a single piece of sheet metal to form a plate or body-portion 13 having a depending front flange 14, and side flanges 15. At its rear edge the finger-head is provided with tongues 16, which are bent down and coiled upon themselves to receive the hinge-pin, so that the upper surface of the finger-head will be supported slightly above the surface of the wooden strip A. In practice, I have found this to be a desirable form of construction, as it leaves the rear edge of the finger-head entirely unobstructed, so that dirt or dust collecting thereon can be pushed back and readily wiped therefrom. In this application for patent, however, I do not wish to claim the construction of finger-head, or the arrangement of hinge-joint for connecting the same with the finger-head-board, as this subject matter is claimed in a patent granted to me March 1, 1904, No. 758,577, the invention which I desire to cover in this application for patent relating more specifically to a special form of porcelain thread-guide, and to an improved construction for securing the porcelain guide in its support, and for adjustably fastening the support to its finger-head.

A support for a thread-guide constructed according to my present invention is provided with a partially closed spring-socket, into which the special form of porcelain thread-guide may be forced or pushed down, so that the mere act of forcing the thread-guide into place will secure the same rigidly and firmly into position. As herein illustrated, the thread-guide-support is preferably formed of sheet metal, and consists of a sheet metal plate 17 having an open throat-way 18 and a thread-guide socket 19. The plate 17 is provided with a marginal flange 20 which extends along the edges of the

plate, and around the thread-guide socket. The marginal flange 20 around the thread-guide-socket is preferably notched or split in a number of places, and may be given a 5 tapered or conical form, as most clearly illustrated in Figs. 5 and 6. Secured in the thread-guide support as thus constructed is a porcelain thread-guide 21, which preferably has a circumferential groove 22 and a 10 bottom flange 23.

The grooved portion 22 of the porcelain guide 21 is preferably of a truncated form, the diameter of the bottom flange 23 being preferably substantially equal to the diameter 15 of the body portion of the porcelain guide immediately under the top flange thereof, and I regard this as an especially desirable form of construction, as I have found in practice, that by forcing a thread- 20 guide of this form into its socket, as illustrated in Figs. 5 and 6, the thread-guide will be clamped and held in a rigid firm manner. It is obvious, however, that the body portion of the thread-guide need not necessarily 25 be of tapering or truncated form, as herein shown.

To adjustably secure the thread-guide supporting-plate 17 to the finger-head, the plate 17 extends loosely through the front flange 14 of the finger-head, and is adjustably 30 clamped in position, so that when the same has been moved in or out, or swung sideways to the desired position, it may then be solidly clamped or fastened. The clamping mechanism preferably employed com- 35

prises a blank-headed screw 24 which extends through clamping-plates 25, and through a slot 27 in the plate 17, with a nut 28 threaded on to the lower end of the screw 24.

I am aware that numerous changes may be made in practicing my invention by those who are skilled in the art, without departing from the scope thereof as expressed in the claims. I do not wish, therefore, to be limited to the construction I have herein shown and described, but

What I do claim and desire to secure by Letters Patent of the United States is:—

In a construction of the class described, 50 the combination of a thread-guide of porcelain having top and bottom flanges forming between them a circumferential groove, and a flat sheet metal plate constituting a holder having a spring-flange adapted to spring 55 into engagement with the groove of the thread-guide between the flanges when the same is forced into place therein, whereby the thread-guide will be frictionally held from turning and displacement by the walls 60 of said spring flange and will project both above and below the sheet metal holder.

In testimony whereof I have hereunto set my hand, in the presence of two subscribing witnesses.

LEWIS T. HOUGHTON.
